UNITED STATES PATENT OFFICE.

WILLIAM EARL MUNSLAW, OF STEUBENVILLE, OHIO.

RAILWAY-TIE.

1,109,539.

Specification of Letters Patent.

Patented Sept. 1, 1914.

Application filed February 17, 1914. Serial No. 819,250.

To all whom it may concern:

Be it known that I, WILLIAM E. MUNSLAW, a citizen of the United States, residing at Steubenville, in the county of Jefferson and State of Ohio, have invented new and useful Improvements in Railway-Ties, of which the following is a specification.

The present invention relates to improvements in metallic railway ties, and means for securing the rails to the ties, and resides in the construction, combination and arrangement of parts set forth in the following specification and falling within the scope of the appended claims.

15 In the drawing: Figure 1 is a top plan view illustrating rails constructed in accordance with the present invention and supporting ties thereon, Fig. 2 is an enlarged central longitudinal sectional view on the line 2—2 of Fig. 1, Fig. 3 is a detail sectional view illustrating the U-shaped connecting member arranged upon the tie before the arms of the same are bent into engagement with the rail, Fig. 4 is a view illustrating 25 the manner for sustaining the said U-shaped member while the arms thereof are bent upon the base flanges of the rails, Fig. 5 is a transverse sectional view on the line 5—5 of Fig. 1, Fig. 6 is a detail perspective view 30 of one of the rail securing members, Fig. 7 is a detail perspective view of a modified form of the tie, Fig. 8 is a central longitudinal sectional view through a still further modified form of the tie, Fig. 9 is a transverse sectional view taken centrally through 35 the rail receiving portion of the tie shown in Fig. 5, Fig. 10 is a view of a tie embodying the features of my invention but being of a different form from those previously 40 described, and Fig. 11 is a detail perspective view of a still further modified form.

In the showing of the drawings I have illustrated a tie constructed of metallic tubes, each being indicated by the numeral 1. The 45 tubes have, what I will term, their upper faces adjacent their ends, bent downwardly to provide flat bearing surfaces or pockets 2 upon which the rails rest. The pockets are provided with a plurality of spaced openings, being arranged upon the flat faces of 50 the pockets at the opposite sides of the base flange of the rail, the inner walls of the said openings being preferably flush with the said longitudinal edges of the base flanges

of the rails, the openings being indicated 55 by the numerals 3.

The numerals 4 designate the securing members for the rails. These members are round, rectangular or square in cross section and comprise a pair of parallel arms 5 and 60 a central bowed connecting member 6. The bowed portion 6 of each of the members 4 is formed of suitable spring material, and the arms 5 thereof are malleable, so that the same will not break when bent over the 65 edges of the rails and upon the upper faces of the base flanges thereof, as will now be described. The arms 5 of the members 4 are arranged within the openings 3 so that the said arms will engage with the opposite 70 longitudinal edges of the rails, and thereafter a jack or other blocking device, indicated by the numeral 7, is inserted through the said end of the tube, so that the bowed end of each of the members 4 is brought into 75 tight contact with the lower flat face of the pocket 2. The projecting side members or arms 5 are then contacted by a hammer and bent tightly over the edge and the upper faces of the base flanges of the rails. When 80 the member 7 is removed the spring 6 will exert a tension to force the bent arms tightly into engagement with the rails and so secure the bent portions of the arms tightly against the rails.

85 In Fig. 7 I have illustrated a tie which may be found efficient in use for supporting a switch, the same including a round body A but which has an upper flat surface B upon which both the main rails and the 90 switch rails may be arranged, the flat surface B being provided with suitable openings to receive the securing members for the main rails.

In Figs. 8, 9 and 10 I have illustrated 95 a tubular tie C which is provided, adjacent its opposite ends, with a depressed flat face D upon which the base flanges of the rails are received, the said surface being of a width corresponding with the width 100 of the base flange, so that the same will contact with the side walls thus provided, and so prevent the lateral movement of the rails when arranged upon the tie, the openings for the arms of the rail securing member being arranged in line with the vertical transverse wall provided by the depressed portion. Furthermore, I have provided 105

each of the said flat surfaces with a central, preferably semispherical, depression E which reinforces the said portions D and does not interfere with the resting of the 5 rails thereon.

In Fig. 10 I have illustrated a hollow tie of a different peripheral formation from those previously disclosed, the said tie being hexagonal shaped and being indicated 10 by the character F. One of the flat faces of the tie F is provided with depressed portions G adjacent its ends which form flat pockets to receive the rails.

It will, of course, be understood that the 15 tubular ties 1 afford a sufficient resiliency to prevent the breakage thereof by the rolling stock passing over the rails which they support, and also that the rails themselves will be afforded the desired amount of re- 20 siliency to prevent their breakage. By constructing the ties of tubes the roadbed may be easily packed around the same, and also a portion of the roadbed may enter the opposite sides of the tie to prevent the 25 lateral movement of the said tie. Again, it is to be understood that the tie is not necessarily restricted to a tubular formation, as other forms of hollow members may be used if desired.

30 In Fig. 11 I have illustrated a hollow metallic tie T of a rectangular formation which has its top plate provided with spaced elongated slots for the reception of the arms 5 of the securing members 4.

35 In the drawings I have illustrated several forms of ties, but it is to be understood that I am not to be restricted to only such forms, as my fastening means may be employed with efficiency upon various other 40 forms or constructions of ties; and may therefore be considered as falling within the scope of my invention.

From the above description, taken in connection with the accompanying drawings, 45 the simplicity of the device as well as the

advantages thereof will, it is thought, be perfectly apparent to those skilled in the art to which such invention appertains without further detailed description.

Having thus described the invention, what 50 I claim is:

1. A metallic tie comprising a tube having a flat depressed portion forming a seat for a rail, the seat having openings arranged to the opposite sides of the rails, 55 rail securing elements for the openings, said elements each comprising spaced arms which extend through the openings and which are constructed of malleable metal, and an outwardly bowed connecting member 60 arranged within the interior of the tie, the ends of the arms adapted to be bent over the edges and base portion of the rail and the bowed connecting member adapted to exert a tension upon the said bent portions. 65

2. A hollow metal tie having spaced openings arranged in pairs, and a rail adapted to be seated upon the tie between the pairs of openings therein, of a securing member 70 for connecting the rail with the tie, said member including a lower bowed portion having parallel angular arms extending therefrom, the said arms adapted to be inserted through two of the openings at each 75 of the opposite sides of the rail, and adapted to be bent over the longitudinal edges of the rail and to straighten the bow-shaped connecting member against the under face of the tie to permit of a constant tension 80 being exerted between the connecting member of the arms and the bent portions of the arms which engage with the rail.

In testimony whereof I affix my signature in presence of two witnesses.

WILLIAM EARL MUNSLAW.

Witnesses:

BERNICE CAMPBELL,
D. M. GRUBER.
